VIBRATING STRIKE-OFF

Everell E. Reed, Denison, Tex.

Application September 9, 1952, Serial No. 308,568

8 Claims. (Cl. 94—45)

This invention relates in general to concrete finishing machinery, and more specifically to a screed attachment for vehicles.

The primary object of this invention is to provide an improved screed attachment for finishing concrete which may be attached to small tractors or other small vehicles for movement along a concreted strip.

Another object of this invention is to provide an improved portable screed attachment for vehicles, said screed attachment being of a relatively simple construction and utilizing readily obtainable power sources whereby the same is economically feasible.

Another object of this invention is to provide an improved portable screed adapted to be attached to small vehicles such as tractors for movement thereby, said screed being easily and quickly attached to and removed from an associated vehicle.

A further object of this invention is to provide an improved strike-off shoe which includes a flat strike-off plate having a recessed edge with curved ends to prevent the working of cementitious materials off of the ends.

A still further object of this invention is to provide an improved screed attachment for vehicles, said screed attachment being adapted to be reciprocated by drive means attached to a power take-off of the vehicle with which it is associated, and vibrated by a vibrating head of a standard vibrator which may be carried by the vehicle.

With these objects definitely in view, this invention resides in certain novel features of construction, combination and arrangement of elements and portions as will be hereinafter described in detail in the specification, particularly pointed out in the appended claims, and illustrated in the accompanying drawings which form a material part of this specification, and in which:

Figure 1 is a top plan view of a conventional tractor which has mounted thereon the improved screed attachment which is the subject of this invention, the screed attachment being shown in the process of finishing a narrow strip of concrete;

Figure 2 is a rotated side elevational view of the tractor and screed attachment of Figure 1, and shows the relationship of the various elements thereof;

Figure 3 is an enlarged top plan view of a strike-off shoe of the screed attachment and shows the general outline of the same, means for supporting and reciprocating the strike-off shoe being omitted;

Figure 4 is a rear elevational view of the strike-off shoe of Figure 3 and shows the general details thereof;

Figure 5 is an enlarged fragmentary front elevational view of a pitman carried by the tractor for reciprocating the strike-off shoe, the pitman having mounted thereon a drag link whose other end is intended to be connected to the strike-off shoe;

Figure 6 is an enlarged front elevational view of a support adapted to be secured to the tractor for supporting hoist means for raising the strike-off blade out of engagement with concrete being finished thereby; and,

2.

Figure 7 is an enlarged transverse vertical sectional view taken substantially upon the plane indicated by the section line 7—7 of Figure 4 and shows the general cross-section of the strike-off shoe.

5. Similar characters of reference designate similar or identical elements and portions throughout the specification and throughout the different views of the drawings.

Referring now to the drawings in detail, it will be seen that there is illustrated a conventional tractor which is referred to in general by the reference character 10. The tractor 10 has mounted thereon the portable screed attachment, which is the subject of this invention, the screed attachment being referred to in general by the reference numeral 12.

15. It will be seen that the portable screed attachment 12 includes an elongated push bar 14 which is connected at one end to a hitch bar 16 of the tractor 10 and extends outwardly to one side of the same. The hitch bar 16 is illustrated as being a generally U-shaped bar connected at its forward ends by suitable fasteners to a rear axle housing 18 of the tractor and is braced by a pair of rearwardly extending diagonal braces 20. However, it will be understood that the hitch bar 16 may be of any conventional configuration. The push bar 14 is braced by a diagonal brace 22 which extends forwardly and inwardly from a point adjacent the outer end of the push bar 14 to a point on the frame on the tractor 10 adjacent the front wheels 24 thereof. It is preferred that the diagonal brace 22 be permanently connected to the push bar 14 and removably connected to the frame of the tractor 10 by suitable fastening means.

20. The push bar 14 is provided on its forward side with ball fittings 24 and 26 which are positioned intermediate the ends thereof and at the outer end thereof, respectively. Connected to the ball fittings 24 and 26 for pivotal movement is a pair of forwardly extending connecting rods 28. The forward ends of the connecting rods 28 are also pivotally connected to ball fittings 30 carried by a strike-off shoe or screed which is referred to in general by the reference numeral 32.

25. Referring now to Figures 3 and 4 in particular, it will be seen that the strike-off shoe 32 includes a flat strike-off blade 34 which extends the full width of the strike-off shoe 32. The strike-off blade 34 is provided with a recessed forward edge 36 which has curved outer ends 38 for engaging cementitious material to strike the same off and simultaneously finish it due to the action of the flat surface of the blade 34. The strike-off shoe 32 also includes a vertical front flange 40 which is secured to the strike-off blade 34 and extends vertically therefrom along the recessed front edge 36 thereof.

30. It will be noted that the ball fittings 30 are carried by the strike-off blade 34 adjacent the outer ends thereof whereby the pushing force exerted thereon by the connecting rods 28 may have the best steadyng effect. Inasmuch as the push bar 14 is rigidly connected to the tractor 10, it will be seen that whenever the tractor 10 is moved along a surface, the strike-off shoe 32 will be propelled alongside the tractor 10 due to the forward urging of the push bar 14 and its associated connecting rods 28. It will be also noted that inasmuch as the connecting rods 28 slope downwardly and forwardly, as is best illustrated in Figure 2, a downward force will be exerted on the strike-off shoe 32.

35. Referring now to Figures 1 and 2 in particular, it will be seen that the tractor end of the diagonal brace 22 is connected to a transverse member 42 which is secured beneath the frame of the tractor 10 and extends outwardly on both sides thereof. The transverse member 42 has its outer ends braced by a pair of rearwardly and inwardly

extending braces 44 which are also connected to the tractor frame.

Also connected to one outer end of the transverse member 42 adjacent its connection with the diagonal brace 22 is a pillow block 46. The pillow block 46 is in longitudinal alignment with a journal member 48 carried by one leg of the U-shaped hitch 16 and a rotatable, drive shaft 50 is journaled in the two. The rear end of the drive shaft 50 is provided with a driven sprocket 52 which is in transverse alignment with a drive sprocket 54. The drive sprocket 54 is mounted on a drive shaft of a power takeoff 56 of the tractor 10 and is connected to the driven sprocket 52 by a drive chain 58 entrained thereover.

Referring now to Figure 5 in particular, it will be seen that the forward end of the drive shaft 50 terminates in a wheel 60 which has mounted thereon eccentric to the shaft 50 a crank pin 62. Pivottally connected on the crank pin 62 for reciprocating movement thereby is one end of a pitman arm 64. The other end of the pitman arm 64 is connected to the strike-off shoe 32 in a manner to be described in more detail hereinafter for imparting a reciprocating motion to the same.

Referring now to Figures 1 and 3 in particular, it will be seen that mounted on the strike-off blade 34 at the rear of the wall 40 is an elongated vibrator head 66. The vibrator head 66 is connected by a flexible drive shaft 68 disposed within a flexible housing 70 to a vibrator unit 72 mounted on the rear of the tractor 10 and connected to either the push bar 14 or the hitch 16. If it should be so desired, the entire vibrator unit may be in the form of a conventional portable vibrator which is secured temporarily on the tractor 10 and the portable screed attachment 12.

Referring now to Figures 1 and 2 in particular, it will be seen that carried by the vibrator head 66 and projecting upwardly therefrom is a ball fitting 74. The ball fitting 74 is pivotally connected to the other end of the pitman arm 64. Inasmuch as the pitman arm 64 is reciprocated by the wheel 60 mounted on the drive shaft 50, it will be seen that reciprocatory motion is imparted to the strike-off shoe 32 thereby.

Referring now to Figure 6 in particular, it will be seen that there is illustrated a generally L-shaped support which is referred to in general by the reference numeral 76. The L-shaped support 76 includes a vertical member 78 which is connected at its upper end to a horizontal boom 80. The boom 80 is braced with respect to the vertical member 78 by a diagonal brace 82 whose ends are secured to the same by suitable fasteners 84.

Referring now to Figures 1 and 2 in particular, it will be seen that the vertical member 78 is secured to the tractor 10 with the boom 80 in the horizontal position. The boom 80 is disposed slightly rearwardly of the strike-off shoe 32 and the end portion thereof extends slightly outwardly of the center of the strike-off shoe. The tractor 10 is provided with a power lift arm 86 which has connected thereto one end of a flexible line 88. The flexible line 88 extends forwardly from the arm 86 and passes around the pulley 90 carried by the boom 80 adjacent the tractor 10. Disposed in a horizontal plane along with the pulley 90 is a second pulley 92 which is carried by the rear side of the boom 80 adjacent the outer end thereof. The outer portion of the second pulley 92 is in alignment with a vertical pulley 94 carried by the underside of the boom 80 and in alignment with the center of the strike-off shoe 32. The flexible line 88 passes through the pulley 90, around the pulley 92 and down over the pulley 94 and is connected to a pair of flexible members 96 which extend upwardly from the strike-off shoe 32.

Referring now to Figure 4 in particular, it will be seen that there is shown a pair of spaced eyes 98 which are in the form of inverted U-shaped members having their free ends rigidly secured to the front wall 40 of the strike-off shoe 32. The lower ends of the flexible lines 96 are connected to the eyes 98 in any suitable manner so that when

the end of the flexible line 88 to which the flexible lines 96 are connected is raised, the strike-off shoe 32 will also be raised.

Referring now to Figures 1 and 2 in particular, it will be seen that the tractor 10 is illustrated as running down an existing strip of road which is referred to by the reference numeral 100. In spaced parallel relation to one edge of the road 100 is an elongated form 102 which, in combination with the road 100, provides a form for concrete 104 which has been poured to provide a widening strip for the road 100. It will be understood that the concrete widening strip is relatively narrow and has a width of from two to three feet. Due to the narrow width of the widening strip, machinery normally utilized for striking off and finishing roadways cannot be utilized.

When it is desired to strike off and finish the widening strip illustrated in Figures 1 and 2, the tractor 10 is driven alongside the same at a very slow speed and the bottom surface of the strike-off blade 34 rides upon the form 102 and an adjacent edge of the road 100. The strike-off blade 34 is then reciprocated transversely of the widening strip at a rate of approximately 60 revolutions per minute and the concrete is smoothly struck off. It will be noted that the strike-off blade and its associated front wall have curved outer ends which engage struck off concrete at the outer ends of the strokes of the strike-off blade so as to prevent the concrete from working off of the ends of the same and being wasted. Simultaneous with the reciprocation of the strike-off blade 34 a vibrating movement is imparted to the strike-off blade whereby the flat lower surface of the same will impart a desired finish to the struck-off concrete.

While the portable screed attachment 12 has been illustrated and described as being mounted on a tractor, such as the tractor 10, it will be understood that the attachment is not so limited inasmuch as it may be conveniently attached to other suitable vehicles which may be driven at a very slow rate and which have power take-off means for driving the drive means for imparting a reciprocating motion to the strike-off shoe. Also, it will be understood that it will not be necessary to utilize a vehicle which is provided with power lift means inasmuch as the strike-off shoe may be manually raised by suitable hoist means.

The operation of this device will be understood from the foregoing description of the details thereof, taken in connection with the above recited objects and drawings. Further description would appear to be unnecessary.

Minor modifications of the device, varying in minor details from the embodiment of the device illustrated and described here, may be resorted to without departure from the spirit and scope of this invention, as defined in the appended claims.

Having thus described the invention, what is claimed as new is:

1. An attachment for a vehicle comprising a push bar, a connecting frame at one end of said push bar adapted to be connected to the rear of the vehicle so that the push bar will project to one side of the vehicle, a screed parallel to said push bar, a pair of parallel connecting rods pivotally connecting said screed to said push bar for relative lateral movement, vibrating means mounted on said screed, and a pitman arm connected to said screed and adapted to be connected to a reciprocating means for reciprocating said screed.

2. An attachment for a vehicle comprising a push bar, a connecting frame at one end of said push bar adapted to be connected to the rear of the vehicle so that the push bar will project to one side of the vehicle, a screed parallel to said push bar, a pair of parallel connecting rods pivotally connecting said screed to said push bar for relative lateral movement, and a pitman arm connected to said screed and adapted to be connected to a reciprocating means for reciprocating said screed.

3. An attachment for a vehicle comprising a push bar, a connecting frame at one end of said push bar adapted to be connected to the rear of the vehicle so that the push

bar will project to one side of the vehicle, a screed parallel to said push bar, a pair of parallel connecting rods pivotally connecting said screed to said push bar for relative movement, vibrating means mounted on said screed, and means connected to said screed for reciprocating said screed.

4. An attachment for a vehicle comprising a push bar, a connecting frame at one end of said push bar adapted to be connected to the rear of the vehicle so that the push bar will project to one side of the vehicle, a screed parallel to said push bar, a pair of parallel connecting rods pivotally connecting said screed to said push bar for relative lateral movement, and means connected to said screed for reciprocating said screed.

5. An attachment for a vehicle comprising a push bar, a connecting frame at one end of said push bar adapted to be connected to the rear of the vehicle so that the push bar will project to one side of the vehicle, a screed parallel to said push bar, a pair of parallel connecting rods pivotally connecting said screed to said push bar for relative lateral movement, vibrating means mounted on said screed, and a pitman arm connected to said screed and adapted to be connected to a reciprocating means for reciprocating said screed, said screed having lift means for selectively elevating said screed to an inoperative position.

6. In combination with a tractor having a power take-off, a push bar rigidly carried by said tractor at the rear thereof and projecting to one side thereof, a screed disposed at said one side of said tractor in front of said push bar, connecting rods pivotally connecting said screed to said push bar, drive means driven by said power take-off

5
10

25
30

connected to said screed for imparting reciprocatory movement to said screed.

7. In combination with a tractor having a power take-off, a push bar rigidly carried by said tractor at the rear thereof and projecting to one side thereof, a screed disposed at said one side of said tractor in front of said push bar, connecting rods pivotally connecting said screed to said push bar, drive means driven by said power take-off connected to said screed for imparting reciprocatory movement to said screed, and hoist means carried by said tractor and connected to said screed for elevating said screed.

8. In combination with a tractor having a power take-off, a push bar rigidly carried by said tractor at the rear thereof and projecting to one side thereof, a screed disposed at said one side of said tractor in front of said push bar, connecting rods pivotally connecting said screed to said push bar, drive means driven by said power take-off connected to said screed for imparting reciprocatory movement to said screed, and a vibrating head carried by said screed, means carried by said tractor for actuating said vibrating head.
